UNITED STATES PATENT OFFICE.

CHARLES E. PRATT, OF CHICAGO, ILLINOIS.

FARE-REGISTER.

SPECIFICATION forming part of Letters Patent No. 357,229, dated February 8, 1887.

Application filed November 13, 1885. Serial No. 152,736. (Model.)

To all whom it may concern:

Be it known that I, CHARLES E. PRATT, a citizen of the United States, residing at Chicago, in the county of Cook and State of Illinois, have invented certain new and useful Improvements in Fare-Registers; and I do hereby declare the following to be a full, clear, and exact description of the invention, such as will enable others skilled in the art to 10 which it appertains to make and use the same.

My invention relates to that class of fare-registers in which dials are used to register the fares of each trip, wheels used to register the number of fares collected on all the trips, and wheels to register the number of trips made.

My invention relates to constructions and combinations, all as will hereinafter be described in the specification, and pointed out in 20 the claims, reference being had to the accompanying drawings, in which—

Figure 1 represents a front view, with portions of the cap A' broken away to show the interior; Fig. 2, a front elevation, with cap A', dials, and front ratchet-wheels removed; Fig. 3, a front elevation with cap A', the dials, and ratchet-wheels removed, the parts of the mechanism shown being in their normal position; Fig. 4, a front elevation similar to that shown 30 in Fig. 3, excepting the details shown in the right-hand side of the latter. In this figure the hammer is about to be released by the triangular pawl d' tripping upon the catch a¹⁵. Fig. 5 is a detail showing the rear of part of the bell-lever; Fig. 6, a horizontal section on line 6, Fig. 3, the several parts all being in place; Fig. 7, a detail showing part of arm A⁵ and the pawl C in perspective; Fig. 8, a detail showing a section on line 8, Fig. 6, the foundation-plate and back of case being omitted; Fig. 9, a section on line 9, Fig. 7; Fig. 10, a plan view of pawl, of arm A⁵, link A⁴, and pawl C; Fig. 11, a detail showing a vertical section taken on line 11, Fig. 2; Fig. 12, a 40 similar view taken on line 13, Fig. 2; Fig. 13, a section taken on line 13, looking in opposite direction to that shown in Fig. 12; Fig. 14, same as Fig. 11, but looking in the opposite direction; Fig. 15, a detail showing the bell-lever in perspective; Fig. 16, an elevation 50 of part of the device and showing the dial, ratchet-wheel B, gear-wheel B', a section of

wheel B⁵, and manner of retaining the disk-wheel b¹⁰ in place; Fig. 17, an elevation of part of the device, showing the manner of retaining the disk-wheel b¹⁰ in place, the tripping-arm B⁸, and the arm E and rod E'; Fig. 18, a detail showing the wheel B⁵ and disk-wheel b¹⁰ in perspective; Fig. 19, an elevation representing the wheel B³, disk-wheel b¹⁰, pawl-wheel B', and the shaft D' and the parts thereon, as will hereinafter be described; Fig. 20, a front elevation of wheels B and B'; Fig. 21, a detail in perspective and showing the shaft D' and some of the parts located thereon; Fig. 22, a rear elevation of the top part of case A, with door H' partly broken away to show the trip-dials E' and E¹⁴, and wheel E⁶, for registering the fares of all the trips. Fig. 23 is an elevation showing the register for all 70 the fares of the trips and the trip-register.

A represents the inclosing-case, having the ears a a, by which it is hung; and A' the cap for the case and provided with glass-covered openings a' and a''.

A² is a foundation or base plate fastened to the inner side of the back of the case. Through the lower side of the case projects an operating lever or rod, A³, slotted at a³ to receive the guide-pin a', attached to the plate A². A link, A⁴, connects the upper end of rod A³ with a reciprocating arm, A⁵. This arm is journaled in the central shaft, A⁷, which is stepped in the base-plate A², as shown in Fig. 6.

The arm A⁵ is provided with a sleeve, a⁵, fitting loosely upon the hub a⁸ of a barrel, A⁸, fixed to the base-plate, and containing a coiled spring, a⁶, having one end attached to the barrel A⁸ and the other to the sleeve a⁵ of the arm A⁵, as shown in Fig. 8. When the arm A⁵ is 85 pulled down by the rod A³ to the position shown in Fig. 4, the spring is coiled tightly, and when the arm A⁵ is released the rebound of the spring draws the arm upwardly to its normal position against the post A⁹. (Shown in Fig. 95 3.) Every time the arm is drawn to the position shown in Fig. 4 the gong A⁹ is sounded by the following means: A ratchet-pinion, A¹⁰, secured to hub a⁸, (see Figs. 3, 4, and 6,) is provided with two sets of teeth, a¹⁰ and a¹², arranged upon opposite sides and inclined toward the same point—that is, in opposite directions, (see Figs. 3 and 4,) and these teeth are alternately engaged by the triangular pawl

A^{13} , pivoted on arm A^5 . The lower inner corner, a^{13} , of the same pawl engages with teeth a^{10} when the arm A^5 is drawn down and forces the outer corner, a^{14} , against a trip-catch, a^{15} , on the arm A^{17} of the bell-lever A^{15} until the latter is drawn up to such a position that when released it will rebound and strike the gong. The pawl A^{13} , when engaged with the teeth on ratchet-pinion A^{10} , also prevents the arm A^5 from being returned to its normal position until after the full stroke is completed, the gong sounded, and the fare registered, as the corner a^{13} will catch in the teeth a^{10} and be held there until the pawl A^{13} is released by the trip-catch a^{15} . The upper inner corner, a^{16} , engages by means of spring a^{20} with the teeth a^{12} when the ringing mechanism is returning to its normal position and prevents the gong from being struck until the parts have reached their normal position.

The bell-lever A^{15} has two arms, the hammer-arm A^{16} and the trip-catch carrying-arm A^{17} . At the angle is an opening which fits over the post a^{18} on the base-plate. (See Figs. 2, 3, and 4.) A hammer-spring, A^{18} , is coiled around this post a^{18} , (see Figs. 2, 3, and 4,) and has its short arm in contact with the post a^{19} and its long arm attached to arm A^{17} , so that when the arm A^{16} of the lever A^{15} is drawn up ready to strike the spring will force the hammer against the gong as soon as the lever is released. The trip-catch a^{15} is pivoted to arm A^{17} , as shown in Figs. 3, 4, 5, and 15, and has a slight oscillating movement, which is stopped by the pin a^{21} on said arm. The inner end of the trip-catch a^{15} has a rearwardly-projecting pin, a^{22} , for the spring a^{23} , Figs. 5 and 15, which returns the trip-catch to its normal position, Fig. 3, and shown fully in Fig. 4.

In front of the ratchet-pinion A^{10} , and fastened by a pin, Fig. 6, to the shaft A^7 , is a ratchet-wheel, B, having ten cogs corresponding with the numerals on the dial B' , which registers the units. This dial is fastened to shaft A^7 , so that when the ratchet-wheel B is moved one cog a corresponding change will be noted on the dial B' through opening a' of the cap A' . In front of the ratchet-wheel B, and loose upon the shaft, is the ratchet-wheel B', attached to the dial B' , registering tens in any suitable manner. This dial is recessed on its face, so that the unit-dial will fit therein. A smaller mutilated gear-wheel, B³, Fig. 6, is formed with or attached to the hub of wheel B², and corresponds with a gear-wheel, B⁴, on the hub of wheel B. The object of wheels B³ and B⁴ will hereinafter be explained.

The ratchet-wheel B is rotated by the push-pawl C, which is pivoted upon the outer end of and moves with the arm A^5 . This pawl consists of the shank c, the wide catch c' , and the forwardly-projecting narrow catch c'' . The inner or wide catch ordinarily contacts with the extreme end of the teeth of wheel B, so that the projecting catch c'' will not contact with the teeth of wheel B². The pawl C is held in that position by the stop C', pivoted

upon the arm A^5 and held in place by a spring, c³, Figs. 6 and 9. Upon the front of stop C' is a projection, c⁴, which extends to a point in front of the arm A^5 , so that when the wheel B is revolved once a fixed beveled projection, b, upon the back of wheel B will contact with and force the stop C' backwardly and out of the way of the pawl C, which is shifted to the position shown in dotted lines, Fig. 10, by the spring c⁵. This movement permits the wide catch c' to drop to the bottom of the recess between the teeth of wheel B and the catch c'' to contact with the extreme end of one of the teeth of wheel B, which is turned once to register the tens on the dial B' . When the next fare is registered, the arm A^5 is drawn down and the pawl C is forced back to the position shown in full lines, Fig. 10, by the next tooth on wheel B. The stop C' is also forced back to its normal position by the spring c³ until the next complete revolution of wheel B.

The wheels B³ and B⁴ are similar in shape, each being mutilated at b³. The mutilation on wheel B³ is not shown, but is similar to that of B⁴. (Shown in Figs. 2 and 20.) These wheels B³ and B⁴ mesh or engage with the teeth of wheel B⁵ at certain times. The wheel B⁵ is mutilated, as shown in dotted lines, Fig. 2, at two opposite points, b⁶, one of which is shown in full lines in Figs. 6, 16, 18, and 19. These mutilations b⁶ are formed by cutting away the back of certain teeth of wheel B⁵, which can still have continuous contact with the barrel-pinion B', mounted on a shaft, D', and shown in Figs. 3, 17, 19, and 21.

The wheels B³, B⁴, and B⁵ are so set with reference to each other as to skip at certain times, so that when the dials are turned back by revolving the wheels B³, B⁴, and B⁵ the mutilated parts b³ and b⁶ will register; and the operator cannot change the position of B³ and B⁴ without registering a fare by pulling upon the operating-lever. Wheel B⁵ is mounted upon a post, b⁶, attached to the face-plate, and connected at the front end by a bridge or plate, b⁷, to shaft D', that carries the pinion B⁶.

On the rear end of the hub or sleeve b⁹ of wheel B⁵ is a hub or disk, b¹⁰, having notches b¹² and b¹³ at diametrical points, and which are alternately presented to the pawl B' as the wheel B⁵ is revolved. The pawl B' is pivoted to the base-plate and held in the lower notch, b¹², by a spring, b¹⁴, attached to a post, b¹⁵, on the base-plate. (See Figs. 16, 17, and 19.) To release the pawl B', a push-pin, b¹⁶, attached by a loop, b¹⁷, Figs. 3, 16, and 17, to the upper arm of the pawl B' and extending to the outside of the case, is used. By pressing upon the outer end of said pin b¹⁶ the lower arm of pawl B' is depressed and the disk b¹⁰, sleeve b⁹, and wheel B⁵ are free to revolve when moved by pinion B⁶. The front face of the disk-wheel b¹⁰, Figs. 16, 17, and 19, is provided with two pins, b¹⁷ and b¹⁸. Pin b¹⁷ is near the outer edge of the disk and is in contact with the tripping-arm B⁸ when the word "down" on the detector-plate or tell-tale D is exposed to the

opening a^2 . Pin b^{18} is near the hub and is in contact with the tripping-arm B^8 when the word "up" on the detector-plate or tell-tale D is exposed through opening a^2 . The tripping-arm B^8 , Figs. 17, 19, and 21, is fixed on the shaft D' , and projects downwardly toward the disk b^{10} , and its lower end is held in contact with one of the pins by the spring b^{19} , coiled around the shaft D' and attached by one end to the tripping-arm, and the other passes behind a screw, d , Figs. 17 and 19. The shaft D' is stepped in the base-plate, Fig. 19, and has rigidly attached thereto the pinion B^6 and ratchet-wheel D^2 , Figs. 3, 16, and 19. The wheel D^2 is prevented from turning, except in one direction, by the pawl d' , held in contact therewith by the spring d^2 , coiled around the shaft and extending over to the pivoted arm E , which is held thereby in contact with the uppermost notch in the disk-wheel b^{10} for a purpose hereinafter described. The tell-tale plate D and the tripping-arm B^8 are journaled upon the shaft D' and connected together by the standard D^3 , having a telescopic section, 25 d^3 , by means of which the tell-tale plate D is adjusted, Fig. 19.

The arm E is pivoted to the base-plate, and normally its catch e , Figs. 3, 16, and 17, is held in contact with the uppermost notch, b^{13} , of the disk-wheel b^{10} by the spring d^2 , and released and pushed upward, as shown in dotted lines, Fig. 17, whenever the pawl B^7 is withdrawn from the lower notch by pressing upon the pin b^{25} and turning the shaft D' in the direction indicated by the arrow, Fig. 16, by means of the button D' . This movement of the shaft D' causes the inclined face of notch b^{13} in disk b^{10} to pass under and raise the catch e and depress the opposite end of the arm E . The opposite end, e' , is provided with a pin, e^2 , which engages with a slot, e^3 , in a rod, E' , that extends upwardly, and is pivoted at e^0 to the rear end of an elongated plate, E^2 , Fig. 14, loose upon the shaft E^3 , and having at its front end a pawl, e^4 , engaging with the teeth of ratchet-wheel E^5 of the unit trip-wheel E^4 , and held in contact therewith by a spring, e^6 , on the arm E^2 , Figs. 2 and 14. The normal position of the arm E^2 is that shown in dotted lines, Fig. 14; and is that produced when the rod E' is in the position shown in full lines, Figs. 16 and 17.

The position of the arm E^2 (shown in full lines, Fig. 14) is that to which it is brought 55 when the rod E' is drawn to the position shown in dotted lines in Fig. 17, and remains in that position until the first fare is registered, when it is changed by the push-finger E^3 , as will hereinafter be described, Figs. 3, 4, 11, and 60 14. This push-finger E^3 is attached to the short arm of arm A^5 , or to the end opposite to that to which the pawl C is attached, and pushes upwardly when the pawl C pushes downwardly. It is pivoted to the arm A^5 by a pin, 65 e^7 , Figs. 3, 4, and 11, having a spring, e^8 , interposed between its head and the push-finger, to hold the latter in an inclined position, Fig.

11, to prevent it from dropping behind the teeth on the ratchet-wheel e^9 on the unit fare-registering wheel E^6 . Upon the rear side of 70 finger E^3 is a pin, e^{10} , which moves in the guides e^{12} , Figs. 2, 4, 11, and 14, that prevent lateral displacement of the latter, Fig. 11.

Between the wheels E^6 and E^7 , and fastened to shaft E^3 , Fig. 13, is a collar, e^{13} , having a 75 wiper, e^{14} , for raising up the pawl e^{15} , pivoted on wheel E^6 and held in contact with the collar e^{13} by spring e^{16} , so that with each revolution of the wheel E^6 the pawl e^{15} will be raised and the part e^{17} forced between two of the projections e^{18} on wheel E^7 , which will be moved to register with the tens. As soon as the next fare is registered the pawl e^{15} passes the wiper e^{14} and returns to its normal position shown in Fig. 13. Wheels E^7 , E^8 , and E^9 are provided 80 with the projections e^{18} , and wheels E^6 , E^7 , and E^8 are provided with pawl e^{15} and springs e^{16} , and the collar e^{13} and wiper e^{14} are placed between wheels E^6 , E^7 , and E^8 . The wheel E^4 on the side opposite to ratchet-wheel e^5 is provided with pawl e^{19} and spring e^{16} , and wheel E^9 has the projections e^{18} , with which the part e^{17} is placed in contact when the wheel E^4 is revolved once by the collar e^{13} and wiper e^{14} , placed between the wheels E^4 , E^6 , E^7 , E^8 , and E^9 . All of these wheels E^4 , E^6 , E^7 , E^8 , and E^9 are provided with spring-clicks e^{19} , Fig. 12, which prevent them from going backward. The dial ratchet-wheels B and B^2 also have spring-clicks B^{10} and B^{12} , which are attached 90 to posts B^3 on the base-plate.

In the back of case A , near the top, is an opening, H , covered by a transparent medium and closed by a door, H' , having appliances for locking, Fig. 22. If desired, either the 105 transparent medium or the door may be dispensed with.

The operation of the device, the parts being in their normal position and the different registering parts indicating zero, is as follows: 110 A fare is to be registered. The lever or handle A^3 is pulled down and oscillates the arm A^5 upon its axis, and at the same time causes the lower corner, a^{13} , of the triangular pawl A^{13} to engage with the teeth a^{10} . This engagement forces the outer corner against the trip-catch a^{15} on the bell-lever A^{15} , which is drawn upwardly until the catch a^{15} trips on the corner a^{14} , when the retracting-spring A^{18} causes the hammer to strike the gong. While the 120 arm A^5 is being turned the pawl C engages with the extremity of the teeth on ratchet-wheel B and turns it one-tenth of a revolution, so that the unit's dial will register "1." 125 As this movement is made the push-finger E^3 forces the elongated plate E^2 to the position shown in dotted lines, Fig. 14, so that the pawl e^4 will engage with one of the teeth of the ratchet-wheel e^5 of the unit trip-wheel E^4 to register the up or down trip. The elongated plate is 130 held in that position until the rod E' is operated by the disk or shaft D' . At the same time the first fare is registered upon the unit-wheel E^6 , which is moved one-tenth of a revo-

lution by the push-finger E⁴. This operation upon wheel E⁶ is continued as each fare is registered. When the tenth fare is being registered, the bevel-faced lug b strikes the stop and permits the wide catch C' to have full contact with a tooth of wheel B, and the narrow catch c' to engage with the end of one of the teeth of wheel B² nearest the catch c' to register the tens. The wiper e⁴ also raises the pawl e⁵ and causes the part e⁷ to pass between the projections e⁸ on wheel E⁷ to register the tens on the latter. As soon as a trip has been made the pin b¹⁰ is pushed in and the pawl B⁷ released from contact with the notch in disk-wheel b¹⁰. As long as the push-pin is pressed upon, the disk-wheel b¹⁰ and the cog-wheel B⁵ are free to turn, and they are turned by means of the head D⁴ of shaft D'. The pinion B⁶ on this shaft turns the wheel B⁸, which in turn acts upon the cog-wheels B⁸ and B⁴, that now present their teeth, instead of the mutilated part, to the wheel B⁵. When the mutilated part is reached, the wheel B⁵ ceases to act upon the wheels B⁸ and B⁴. It will be noted that the ratchet-wheel D² and pawl d' prevent the shaft D' from being turned back; or, in other words, after the operator starts to turn the dials back to zero he cannot ring the bell or register a fare until zero is reached. When the wheel B⁵ begins to turn forward, the pin b¹¹ trips the arm B⁸, and the spring b⁹ causes the tell-tale plate to pass across the opening a², and remains in that position until the pin b¹² catches and draws it back sufficiently to show the word "up" through the opening a². After the pawl B⁷ has been withdrawn from the notch in disk-wheel b¹⁰ and the wheel B⁵ turned, the arm E is thrown out of contact with the upper notch b¹³, of the disk-wheel b¹⁰, and its catch e slides over the periphery of disk-wheel b¹⁰ and draws the rod E' to the position shown in dotted lines, Fig. 17, where it remains until the push-finger E⁸ strikes the elongated plate E', which is now in the position shown in full lines, Fig. 14, and retains the plate E' in the position shown in dotted lines, Fig. 14, and the rod in the position shown in full lines, Figs. 16 and 17. These last described positions are produced as soon as the first fare of the new trip is registered. The arm E returns to its former position as soon as the notch that was formerly the lower one has reached the position that was occupied by the former one; or if wheel B⁵ were completely revolved it will take or rest in the first-named notch. The slot in rod E' permits the return movement independently of the arm E.

What I claim as new is—

1. In a fare-register, the combination, with the units and tens dials, each having a ratchet-wheel, one of which is provided with a beveled lug, b, of a pivoted arm having a pawl provided with a wide and narrow catch, and a stop, C, for said pawl, operated by the beveled lug, and means, substantially as described, for operating the pivoted arm.
2. In a fare-register, the combination, with

the units and tens dials, each having a ratchet-wheel, one of which is provided with a beveled lug, b, of a pivoted arm having a pawl, a stop, C, for the pawl, a spring, c⁵, for returning the stop to its normal position and a spring for turning the pawl, and means, substantially as described, for operating the arm.

3. In a fare-register, the combination of a shaft, A', the dial-plates on said shaft, and each having a ratchet-wheel, a pivoted arm upon said shaft, and having a pawl on one end for the ratchet-wheels on the dial-plates and on the other end a push-finger, a shaft, E³, registering or adding wheels upon shaft E³ and operated by the push-finger, an elongated plate, E', on said shaft E³, trip-wheels operated by said elongated plate, and means, substantially as described, for operating said pivoted arm 85 and elongated plate, substantially as described.

4. In a fare-register, the combination of a shaft, E³, a series of adding-wheels on said shaft, and having means for revolving each other at stated intervals, trip-registering wheels on said shaft, an elongated plate, E', connected with said trip-registering wheels, a pivoted arm having a push-finger for operating the adding-wheels, and means, substantially as described, for operating the elongated plate 95 and pivoted-arm.

5. In a fare-register, the combination of a pivoted arm having means for moving it up and down, a trip-register mounted loosely upon a shaft, and a spring-held pawl pivoted thereon 100 and connecting said plate and trip-register, a rod attached to one end of said elongated plate, and a push-finger on said pivoted arm for returning the elongated plate to its normal position, substantially as described. 105

6. In a fare-register, the combination of a shaft, A', the dial-plates each having a ratchet-wheel, a pivoted arm having a pawl on one end and a push-finger on the other end, an elongated plate which is returned to its normal position by the push-finger, a trip-wheel operated by said elongated plate, a rod for moving said elongated plate, and means, substantially as described, for operating said rod and pivoted arm. 110

7. In a fare-register, the combination of a pivoted arm having means for operating it, a push-finger upon one end of said arm, a shaft, E³, an elongated plate mounted loosely upon said shaft, a trip-register connected to said 120 plate by a spring-held pawl, a rod connected by one end to said plate, an arm, E, connected by one end with said rod and by the other to a notched disk-wheel, and said disk-wheel having means, substantially as described, for 125 revolving it.

8. In a fare-register, the combination of a trip-registering mechanism, a rod connected by one end with said trip-registering mechanism, an arm, E, attached by one end to said rod 130 and by the other end to a notched disk-wheel, b¹⁰, said disk-wheel having the notches b¹² and b¹³, and means, substantially as described, for operating said disk-wheel.

9. In a fare-register, the combination of the trip-registering mechanism, disk-wheel b^{10} , having notches, the arm E, held in contact with one of said notches, the rod E', operated by said arm and connected with said trip-registering mechanism, and a spring-held pawl operated by a push-button, substantially as described.
10. In a fare-register, the combination of a pivoted arm having a pawl and means for moving it up and down, the dials having the mutilated gear-wheels, a shaft having means for revolving it, a pinion upon said shaft, and an idle-wheel connecting said gear-wheels and pinion, substantially as described.
11. In a fare-register, the combination of a pivoted arm having a pawl and means for moving it up and down, the dials having mutilated gear-wheels, a shaft having a pinion and means for revolving it, a ratchet-wheel on said shaft, a spring-held pawl for said ratchet-wheel, and an idle-wheel connecting said mutilated wheels and the pinion, substantially as described.
12. In a fare-register, the combination of the dials having the mutilated gear-wheels and means for moving the dials to register the fares, a shaft having a pinion and means for revolving it, a ratchet-wheel having a spring-held pawl, and an idle-wheel connecting said gear-wheels and pinion.
13. In a fare-register, the combination of the dials having the mutilated gear-wheels and means for moving the dials to register the fares, a shaft having a pinion, an idle-wheel connecting said wheels and pinions and having a notched disk-wheel, and a spring-held pawl for said disk-wheel and provided with a push-pin operated from the outside, substantially as described.
14. In a fare-register, the combination of the dials having the mutilated gear-wheels and
- means to move the dials to register the fares, a shaft having a pinion and means for revolving it, and an idle-wheel having the back of some of its teeth cut away, substantially as described.
15. In a fare-register, the combination of the disk-wheel having the pins upon its front face, a spring-held tripping-arm in contact with one of the pins, and the tell-tale plate connected with said tripping-arm, substantially as described.
16. In a fare-register, the combination of the disk-wheel having the pins upon its front face and notched periphery, the spring-held pawl in said notch, a push-pin for operating said pawl, a tripping-arm in contact with one of the pins, and the tell-tale plate connected with said tripping-arm, substantially as described.
17. In a fare-register, the combination of the case having cap A', the telescopic standard, and the tell-tale plate which is adjusted to and from said cap by means of said standard, substantially as described.
18. In a fare-register, the combination of the adding-register, the arm A⁵, having means for moving it up and down, the push-finger, the pivoted pin, and the spring between the head of the pin and the push-finger, substantially as described.
19. In a fare-register, the combination of the base-plate having guides, the pivoted arm A⁵, and the push-finger pivoted to the arm A⁵ by a pin having a spring interposed between its head and the push-pin, substantially as described.

In testimony whereof I affix my signature in presence of two witnesses.

CHARLES E. PRATT.

Witnesses:

HARRY SMITH,
L. B. COUPLAND.
